US0D1078269S

(12) United States Design Patent (10) Patent No.: US D1,078,269 S
(45) Date of Patent: * Jun. 10, 2025

(54) STORAGE BOX

(71) Applicant: Zhijie Ding, Dong'an County (CN)

(72) Inventor: Zhijie Ding, Dong'an County (CN)

() Term: 15 Years

(21) Appl. No.: 29/996,577

(22) Filed: Apr. 1, 2025

(30) Foreign Application Priority Data

Nov. 14, 2024 (CN) 202430721409.7

(51) LOC (15) Cl. 03-01

(52) U.S. Cl.

USPC D3/279; D3/289; D6/661; D6/671

(57) CLAIM

The ornamental design for a storage box, as shown and described.

DESCRIPTION

FIG. 1 is a front, right, and top perspective view of a storage box, showing the claimed design;

FIG. 2 is a rear, left, and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the storage box that form no part of the claimed design.

1 Claim, 8 Drawing Sheets
